UNITED STATES PATENT OFFICE.

GEORGE D. KINSEY, OF BROOKLYN, NEW YORK, ASSIGNOR TO THE AUSTRALIAN KNITTING COMPANY, OF PATERSON, NEW JERSEY.

DESIGN FOR A KNITTED FABRIC.

SPECIFICATION forming part of Design No. 19,095, dated May 14, 1889.

Application filed April 12, 1889. Serial No. 307,031. Term of patent 7 years.

To all whom it may concern:

Be it known that I, GEORGE D. KINSEY, of Brooklyn, in the county of Kings and State of New York, have invented and produced a new and original Design for Knitted Fabrics, of which the following is a specification.

The accompanying drawing illustrates a design embodying my invention, the design being shown in the white portions of the figure.

The design consists, essentially, of parallel straight lines A A upon the outer edge. Intermediate of the lines A A are approximately diamond-shaped figures B C, which diamond-

shaped figures are arranged in pairs, but are shown as united by substantially straight and parallel lines a. Between each of the figures B C, composing a pair, there extend inwardly from the lines A A dot-like figures b.

What I claim as my design is—

The design for knitted fabrics, substantially as herein shown and set forth.

GEORGE D. KINSEY.
